UNITED STATES PATENT OFFICE.

ROYAL E. TERHUNE, OF CLIFTON, NEW JERSEY.

AIR FILTER.

Application filed August 20, 1923. Serial No. 658,472.

To all whom it may concern:

Be it known that I, ROYAL E. TERHUNE, a citizen of the United States, and a resident of Clifton, in the county of Passaic and State 5 of New Jersey, have invented a new and Improved Air Filter, of which the following is a full, clear, and exact description.

The present invention relates to new and useful improvements in filtering devices, and 10 it pertains particularly to a filtering device especially adapted for filtering air taken into carbureters of internal combustion motors.

It is one of the primary objects of the invention 15 to provide means for filtering the air taken into the intake pipe of internal combustion motor carbureters in order to insure a cleaner mixture of combustible charge.

It is a further object of the invention to 20 construct the filter in such a manner that the several parts thereof are readily removable for the purpose of renewal or cleaning.

It is a still further object of the invention 25 to construct the device in such a manner that all air entering the carbureter will be caused to pass through the filtering elements, thus insuring a complete filtering of the air.

With the above and other objects in view, 30 reference is had to the accompanying drawings, in which

Figure 1 is a view in elevation partly in section, of a device constructed in accordance with the present invention;

Fig. 2 is a longitudinal sectional view 35 thereof taken on the line 2-2 of Fig. 1;

Fig. 3 is a transverse sectional view taken on the line 3-3 of Fig. 1.

Referring more particularly to the drawings, the device comprises a housing 5 having open oppositely-disposed sides 6. The housing is preferably in the form of a cast metal box having a tubular extension or thimble 7 at one end and an integral lug 8 at the opposite end, said integral lug 8 being provided with a perforation or opening 9.

The open sides of the box-like member 50 are each defined by an inwardly projecting flange 10, forming a seat 11 extending entirely around each of the open sides, and said sides are adapted to receive or support the filtering elements 11'. These filtering elements are formed of suitable porous ma-

terial and are formed with openings 12 located in such a manner that as the filtering elements are positioned on the flanges 10, the openings in one of the elements will be opposite the openings in the other element in order that bolts 13 may be passed therethrough for the purpose of securing the filtering elements in position.

The tubular extension or thimble 7 is internally screw-threaded as at 14 for the purpose of receiving a pipe 15, which is 65 connected to the carbureter (not shown), and adjacent the tubular extension 7 a plurality of openings 15' are provided, the purpose of which will be hereinafter described, and this thimble is formed by gradually contracting the bore along gentle curve stream lines, as clearly shown in Fig. 1.

The device is adapted to be supported in place by means of bolts or the like, which pass through the openings 15' and the opening 9 in the lug 8. The pipe 15 having been connected to the air intake of the carbureter in any desired manner, as the motor is started air will be drawn through the filtering elements 11' into the interior of 80 the box-like member 5, and by means of the pipe 15 will pass to the carbureter.

When it is desired to clean the device, it may be removed and air or fluid under pressure may be forced into the box-like member 85 5, and in passing outwardly through the filtering elements 11', will remove all foreign matter from the exterior thereof.

To remove the filtering elements, it is only necessary to loosen the nuts of the bolts 90 13, remove the bolts, and the filtering elements 11' may be readily removed from the sides of the box.

It will be noted that gaskets 20 are interposed between the flange 10 and the respective filtering elements 11' in order to allow for expansion and contraction of the elements 11', caused by temperature changes, and to form an air-tight connection between the filtering elements and the flange and 100 insure all air passing through the filtering elements.

My object in shaping the tubular extension or thimble 7, as herein disclosed, is 105 that by such construction a stream line flow of filtered air from the plates 11' to the exit end of the filter is assured; this increases the efficiency of the device as such

flow allows a smooth undisturbed transmission of the filtered air away from the plates 11' without any friction.

What is claimed is:

- 5 A device of the character described comprising an integral oblong box-like housing, said housing being formed with oppositely disposed open sides, a straight shoulder defining each of said open sides, said shoulders 10 each being set within the box and spaced relative to the defining edge of its respective open side, a gasket carried by each of said shoulders, a filtering element mounted in

each of said open sides and with the gaskets adapted to form a closure therefor, and spaced apart bolts passing through the said filtering elements to regulate their tension and maintain them in position on the gasketed shoulders of the housing, and a filtered air outlet thimble at one end of said 15 housing, said thimble consisting of a tubular extension having a stream-line bore communicating directly with the space between said filtering elements.

ROYAL E. TERHUNE.
